FIG.1

FIG.2

FIG.5

FIG.3

FIG.6

FIG.4

FIG. 1 is a perspective view of a motor pump housing or the like for a dental jet cleansing unit embodying our new design;

FIG. 2 is a front elevation thereof;

FIG. 3 is a left side elevation thereof;

FIG. 4 is a right side elevation thereof;

FIG. 5 is a rear elevation thereof; and

FIG. 6 is a top plan view thereof.

The broken line representation of the electric cord is fragmentarily shown for illustrative purposes only.

The dominant features of our design reside in those portions shown in full lines in the drawings.

We claim:

The ornamental design for a motor pump housing for a dental jet cleansing unit or the like, as shown and described.
